(57) **CLAIM**

The ornamental design for a camera, as shown and described.

DESCRIPTION

FIG. 1 is a front, left, and top perspective view of a camera embodying the new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a rear, right, and bottom perspective view thereof;

FIG. 9 is a front, left, and top perspective view thereof, shown with the display screen in an open position and in a first alternate configuration;

FIG. 10 is a left side elevational view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a front, left, and top perspective view thereof, shown with the display screen in a second alternate configuration;

FIG. 16 is a front, left, and top perspective view thereof, shown with the display screen in a third alternate configuration; and,

FIG. 17 is a left side elevational view thereof.

The broken lines shown in the drawings are included for the purpose of illustrating portions of the camera that form no part of the claimed design. Additionally, the dot-dash broken lines denote the boundary of the claim and form no part of the claimed design.

1 Claim, 17 Drawing Sheets
